UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

CONTAINER.

1,284,686.

Specification of Letters Patent. Patented Nov. 12, 1918.

Application filed July 31, 1915. Serial No. 42,897.

To all whom it may concern:

Be it known that I, JOHN M. HOTHERSALL, a citizen of the United States, residing in Brooklyn, in the county of Kings and State 5 of New York, have invented a new and useful Improvement in Containers, of which the following is a specification.

This invention relates in general to containers for shaving soap, tooth paste, soap 10 paste or the like.

It has for a principal object the provision of a container of this character from which the contents will be fed as desired for use through simple manipulation of the parts 15 of the container.

A further object of the invention is the provision of a container for shaving soap, shaving cream, tooth paste and the like in stick form from which the contents may be 20 fed as desired and the parts of which will be relatively rigid so that the container will present a pleasing appearance even when nearly or wholly empty. In packaging tooth paste and shaving paste or cream 25 prior to my invention, it has been generally the custom to inclose the substances in collapsible tubes of soft foil, the end from the closure being rolled upon itself as the contents are exhausted. This type of package 30 soon becomes out of shape and any advertising labels or other indication of manufacture hidden or at least rendered unsightly.

It is a purpose of this invention to provide a container for these substances which, 35 while possessing the desired ejecting qualities, will at the same time remain of pleasing appearance with advertising labels and the like prominently and attractively displayed.

Shaving soap of stick form has heretofore 40 generally been marketed in containers from which the stick is taken for use. This manner of packaging shaving sticks has exposed the stick to the moisture of the air, for frequently the users have not returned the stick 45 to the container between the times of its use.

A further object of this invention is the provision of a container in which the body of the shaving stick, if the container be used for the packaging of a shaving stick, will 50 remain in the container and be protected from softening under atmospheric moisture and also from moisture caused by wetting too great a portion of the body and soap.

Other objects and advantages of the in- 55 vention will be apparent as it is better under-

stood from the following description when considered in connection with the accompanying drawing illustrating a preferred embodiment thereof.

Referring to the drawing,

Figure 1 is a side view shown partially in section of a shaving stick formed for insertion in a container embodying my invention;

Fig. 2 is a section through such a container;

Fig. 3 is a transverse section through the same showing the soap in position;

Fig. 4 is a side elevation of the container.

Referring to the drawing in which is disclosed an embodiment of the invention constructed for marketing shaving soap, it will be noted that the container comprises a cylindrical side wall 11 corrugated at 12 to form an internal screw thread 13 and having a rotatable bottom 14 carrying an upwardly projecting stud 15. The corrugations 12, which are disposed spirally to form the screw threads 13, extend only throughout the upper part of the container length, leaving a lower smooth surface 16 for the 70 reception of a label. The lower end of the cylindrical wall is necked out at 17 to permit permanent engagement by the bottom 14 which, in the present instance, is provided with an upwardly extending flange 75 at 18 turned in at 19 to embrace the bottom end of the container. The stud 15, in the present instance, consists of a rectangular bar mounted centrally and secured at its bottom at 21 on the bottom wall, so that 80 when the bottom wall rotates the bar 15 will also rotate. The shaving stick generally designated at 22 is provided throughout its length with an external screw thread 23 adapted to engage within the screw threads 85

13 of the container body, and it has an opening or slot 24 for the reception of the stud 15. As the stud 15 is rectangular it has one or more surfaces disposed off the curve of rotation or out of concentric relation 100 with the axis of movement of the bottom, so that rotation of the soap stick occurs when the bottom is rotated, causing a movement of the stick within the container, the internal movement moving it out for shaving and rotation in the opposite direction withdrawing it back into the container thereafter. The stick of soap formed as described may be inserted in the container by threading it over the stud 15 and rotating 105 165 110

the bottom to draw it down into place. An ordinary slip cover 25 is preferably provided.

It is thought that the invention and many of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof.

I claim:

- 15 1. A container having a removable closure and having its side wall formed into an internal screw thread, and having also a bottom rotatable with respect to said side wall, a solid stick of soap or the like in the container having a screw-thread engagement with said internal screw thread, and a diametrically elongated stud attached to said bottom and extending upwardly within said container and having a non-rotary and longitudinally sliding engagement with the said stick for causing the same to be rotated and to rise in the container when the bottom is rotated.
- 20 2. A container having a removable closure and having its side wall formed into an internal screw thread, and having also a bottom rotatable with respect to said side wall, a solid stick of soap or the like in the container having a screw thread engagement

with said internal screw thread, and a stud 35 attached to said bottom and extending upwardly within said container and having a non-rotary and longitudinally sliding engagement with the said stick for causing the same to rise in the container when the bottom is rotated.

3. A container comprising an internally threaded cylinder body, a bottom rotatable with respect to said body and having an upwardly projecting stud, and a solid soap-stick which is externally screw threaded to fit the thread of said body and which is formed with a longitudinal opening having a non-rotary sliding engagement with said stud.

4. A container comprising an internally screw threaded body, a stud within said body and extending longitudinally thereof, and a solid soap-stick which is externally screw threaded to fit the said thread of the body and which is formed with a longitudinal opening having a non-rotary and sliding engagement with said stud, and means for rotating said stud relative to the container body.

In witness whereof I have hereunto set my hand in the presence of two subscribing witnesses.

JOHN M. HOTHERSALL
